UNITED STATES PATENT OFFICE.

HERMAN HEYN, OF OMAHA, NEBRASKA.

PHOTOGRAPHIC MASK.

1,116,888.

Specification of Letters Patent.

Patented Nov. 10, 1914.

Application filed December 8, 1913. Serial No. 805,193.

To all whom it may concern:

Be it known that I, HERMAN HEYN, a citizen of the United States, residing in the city of Omaha, county of Douglas, and State of Nebraska, have invented certain new and useful Improvements in Photographic Masks, and have described the same in the following specification, illustrated by the accompanying drawings.

10 A photographic mask is a thin cover, impervious to actinic rays, which is used in photographic printing to hide that marginal portion of the negative which is not to be printed from, and to expose, through an 15 opening in the middle of the mask, only so much of the negative as is to be reproduced in the photograph.

My invention relates to that class of masks of this kind in which the size of this middle 20 opening is varied from time to time, according to the size of the print, by the manual adjustment of a pair of connected and relatively movable mat strips, or sections.

It is the object of the invention to facilitate, in masks of this class, the mutual adjustment of the mat strips; to effect such 25 adjustments independently of the printing frame; to insure a close contact between the inner margin of the mask and the surface 30 of the negative; to render the joints between the mask strips impervious to light; to facilitate placing the sensitized paper in predetermined positions upon the mask; and in general to produce a photographic mask of superior efficiency. To 35 accomplish these objects I incorporate in my improved mask a pair of flat slideable mat strips, having angularly related arms; a thin gage, slideable on the face of one of the 40 mask strips; covered spring clips, of a special type, connecting one of the mat strips with the other and with the gage; and flexible wings, fringing the inner margins of those strips.

45 In the accompanying drawings, illustrating the best manner in which I have contemplated applying the principles of the invention, Figure 1 is a plan of a mask of the specified class, constructed in accordance 50 with these principles. Fig. 2 is an enlarged section on the vertical section line of Fig. 1. Fig. 3 is a portion of Fig. 1 enlarged. Fig. 4 and Fig. 5 are a plan and a central vertical section respectively of one of the clips by 55 which parts of the mask are slidably connected.

In this illustrated and illustrative specimen of my invention the mat strips 11 and 12, being duplicate flat sheets of dark colored thick paper or thin cardboard, comprise severally, like a carpenter's square, two opaque arms, 13 and 14, or 13' and 14', as the case may be, which are disposed at right angles to each other, and are severally of uniform width. These mat strips are placed slidingly one upon the other, with the arms of each crossing those of the other at right angles, as shown, and are retained in that intersecting position by two sliding metallic clips 15, which are located at the crossings of the arms respectively and illustrated by the Figs. 4 and 5. Each clip is an elastic plate resembling in form a Greek cross, and having its equal arms 16 slightly offset from each other and from the plane of their common intersection in pairs, in the direction of their thickness, as shown in Fig. 5. One pair of these arms of each clip is passed through a pair of longitudinal slits 17 in one of the arms of one of the mat strips; while the other pair of arms of the same clip is passed through the similar slits 17 in the contiguous arm of the other mat strip. To facilitate the sliding of the mat strips, for purposes of adjustment, on these clips, each of the arms 16 has on its inner face a boss, or projecting portion, 18, which is formed by indentation of the outside of the clip. To the inner margin and outer face of each mat arm is glued or otherwise united a thin and flexible strip of dark paper, or opaque fabric, marked with a graduated scale and forming the longitudinally disposed and overhanging wing 19, as shown in Fig. 2, adapted by bending to 95 make with the face of the negative close contacts impervious to light.

At one corner of the under mat strip is superposed thereon a flat angular piece of dark cardboard of similar form, constituting the stop gage 20, which is adjustably attached to both arms of that strip by the clips 15', and the slits 17' of the kind and arrangement already described. The clips 15 and the slits 17 in which they move are in each instance covered by a patch 21, of dark paper or the like, whose marginal portions, beyond the reach of the clips, are glued to the exposed face of the mat strips.

Operatively the graduated scale facilitates the accurate adjustment of the mat strips by the hand of the operator, accord-

2
ing to the desired extent of the exposure of the negative; while the gage enables him to place a number of pieces of sensitized paper successively in one and the same position 5 over the central opening of the mask for printing.

It will be understood that in the adjusting of the mat strips the clips of either pair move only in directions normal to each 10 other; and that the negative, the mask and the sensitized paper may be placed in the usual printing machine in the usual manner. The patches 21 neatly inclose the clips and prevent the passage of light through the 15 slits.

I claim as my invention—

1. A mask of the specified class, comprising a pair of mat strips having angularly disposed intersecting arms, in combination 20 with a pair of sliding clips connecting the arms at their intersections respectively.

2. A mask of the specified class, comprising two contactually intersecting mat strips composed severally of two angularly disposed conjoined arms having a pair of longitudinal slits in each arm, in combination 25 with a plate clip having two pairs of oppositely directed arms, which are united at their common junction between the mat 30 strips, are offset through those slits in pairs, and make sliding contacts with the noncontiguous sides of the mat strips respectively.

3. A mask of the specified class, comprising two contactually intersecting mat strips 35 composed severally of two angularly disposed arms having longitudinal slits, in combination with two connecting clips slideable in the slits and connecting the arms at their intersections respectively.

40 4. A mask of the specified class, comprising mat strips having longitudinal slits, in combination with a plate clip having two pairs of oppositely directed arms, which are united at their common intersection between the mat 45 strips, are offset through the

slits in pairs, and make sliding contacts with the outside faces of the mat strips respectively.

5. A mask of the specified class, comprising 50 mutually contacting mat strips having slits, a clip having arms offset through the slits and sliding on the noncontacting sides of the strips, in combination with flat covers, adhering to the strips and spanning the slits and the clip arms. 55

6. A mask of the specified class, comprising 60 mat strips having angularly disposed intersecting arms, and a stop gage attached to one of the strips and slidable thereon in two angular directions.

7. A mask of the specified class, comprising 65 mutually adjustable mat strips, a stop gage having angularly disposed arms, and sliding clips fastening the arms respectively to one of the mat strips.

8. A mask of the specified class, comprising 70 mutually adjustable mat strips having flexibly attached marginal wings.

9. A mask of the specified class, comprising 75 mutually adjustable mat sections having graduated and flexibly attached marginal wings.

10. A mask of the specified class, comprising a mat strip having angularly disposed pairs of parallel slits, a flat stop gage 80 thereon having angularly disposed arms and longitudinal slits therein, and two plate clips having severally two pairs of oppositely directed arms, which are united at their common intersection between the strip 85 and the gage, are offset from each other in pairs, and make sliding contacts with the noncontacting sides of the strip and the gage respectively.

In testimony whereof I subscribe my name 85
hereto in the presence of two witnesses.

HERMAN HEYN.
